INTERLOCK

Walter F. Regenhardt, Cleveland, Ohio

Application November 12, 1940, Serial No. 365,231

8 Claims. (Cl. 189—36)

The present invention relates to an interlock and more particularly to an interlock for attaching two generally flat elements together. This invention is an improvement over my invention disclosed in my application Serial No. 240,177, filed November 12, 1938.

An object of the present invention is to provide for interlocking two generally flat elements by a generally flat key, the flat elements having registering openings for receiving a leg of the key and the leg of the key having a shoulder which abuts the edge of the opening in one of the elements to prevent accidental withdrawal of the key.

Further objects and advantages will be apparent from the following description, reference being had to the accompanying drawing wherein a preferred form of embodiment of the present invention is clearly disclosed.

In the drawing:

Fig. 1 is a longitudinal sectional view of a plurality of individual file cases showing the lower part of one case interlocked with the top portion of another case and the lower portion of a third case about to be positioned on the top of the first mentioned case, the section of the lower two cases being taken on line 1—1 of Fig. 2;

Fig. 2 is a top view, in section, of the file cases shown in Fig. 1, the section being taken on line 2—2 of Fig. 1;

Fig. 3 is a fragmentary view, in section and on a larger scale, showing interlocking parts of the cases, the section being taken on line 3—3 of Fig. 2, and

Fig. 4 is a top view of the improved locking key.

Although, the present invention relates generally to interlocking two elements, for the purpose of illustrating a preferred form of the invention, I have shown a plurality of individual file cases interlocked wall to wall by my invention. In the specific illustration, the file cases are shown in stacked relationship.

Referring to the drawing, there is shown in Fig. 1 a fragmentary sectional view of the lower part of a case 20, a sectional view of a case 21 and a fragmentary sectional view of the upper part of a case 22. These cases are adapted to be stacked and interlocked for forming a unitary filing cabinet. Each of the cases comprises a sleeve formed by a sheet of metal, which sleeve includes side walls 25 and 26, a bottom wall 27 and a top wall 28. The ends of the sheet forming the sleeve may be secured together, preferably at the bottom by butt welding or overlapped

and then welded as is shown in Fig. 2. A reinforcing ring 30 is disposed within the front end of the case and is suitably secured to the sheet metal walls as by welding. The back of each case is closed by a sheet metal wall 31. Each of the cases receives a drawer (not shown) through the open front thereof and the rear of the bottom wall of the drawer may be provided with spaced gliders for supporting the rear portion of the drawer. The construction thus far specifically described is similar to the file cases shown in my Patent No. 2,123,803 issued July 12, 1938.

The top wall of each of the cases is pierced and bent to form two spaced openings 37 and ledges 38. The bottom wall of each case is similarly pierced and bent to provide two spaced tongues 39, which tongues are adapted to be received in the openings 37 in the top wall of another of the cases. The tongues 39 are inserted 15 in the openings 37 by placing one case on the top wall of another case, with the side walls in alignment, and then sliding the uppermost case rearwardly as is clearly illustrated in Fig. 1. The tongue 39 is adapted to engage the underside 20 of the top wall of the lower case for preventing 25 the rear of the upper case from being raised from the lower case.

The front ends of the cases are attached by my improved interlocking mechanism. This 30 mechanism is formed by piercing the bottom walls of the cases to provide two spaced openings 41 and shearing and bulging the top walls of the case to form projecting or locking members 42. The locking members 42 are adapted to extend 35 through the openings 41 when one of the cases is stacked on the other with the tongues 39 in the opening 37 as described above. This is shown in the lower left hand part of Fig. 1 and in Fig. 3. The side walls of the openings 41 are arranged 40 to closely embrace the side walls of the locking members 42 for maintaining the cases in alignment.

The drawn locking members 42 form recesses 43 on the undersides thereof and the rear ends 45 thereof are open for forming mouths 44 of the recesses 43. The mouths 44 register with the openings 41 to form passages between the cases. The front sides of the members 42 form shoulders 45 and the undersides of the top wall of the members 42 provide abutments 46 facing the walls 27 and 28 when the members 42 are inserted through the openings 41 in the wall 27. When the members 42 are in position in the openings 41, part of the mouths of the recesses 43 and part of the shoulders 45 project above the

bottom wall 27 of the next upper case. It is to be understood that the openings 41 and the locking members 42 may be provided on any of the adjacent walls of the cases but in the preferred embodiment the openings 41 are formed in the bottom wall 27 and the locking members 42 are formed on the top wall 28.

A key 47 is provided for interlocking the adjacent walls of the cases. Preferably this key is formed of flexible resilient sheet metal and is furcated for forming key legs 48 connected by a yoke 49 and an intermediate leg section 50 extending from the yoke 49. Portions of the key legs 48 are depressed for forming downwardly extending cams 51, the rearward ends of these cams forming shoulders 52. The fore part of the section 50 is provided with two outwardly projecting portions 54 which form rearwardly facing shoulders 55 that are adapted to abut the shoulders 45 of the locking members 42 when the key 47 is in locking position. The key 47 is inserted in its locking position by placing the forward part of section 50 upon the tops of the locking members 42 and forcing the ends of legs 48 downwardly into alignment with the mouths 44 of the recesses 43, and then pulling the key forwardly until the projecting portions 54 of the section 50 are moved over the forward ends of the locking members 42. Since the key 47 is formed of resilient material the section 50 can be flexed relative to the legs 48 to move the projecting portions 54 over the tops of the locking members and the portions 54 are then biased against the wall 27 in alignment with the shoulders 45. The shoulders 55 on the portions 54 are adapted to abut the shoulders 45 of the locking members 42 to aid in preventing accidental removal of the key 47. When the key is in the locking position, the legs 48 extend alongside the abutment 46 on the interior of the lower case and the cams 51 of the legs 48 are in the openings 41 and the shoulders 52, formed by the cams 51, are in alignment with shoulders 57 formed by the edge of the openings 41. The shoulders 52 and 57 abut one another when the key is urged rearwardly, with respect to the cases, for preventing accidental removal of the key.

The material from which the key 47 is formed is sufficiently flexible so that leg 50 can be lifted either by one's finger or a small tool, and in order to unlock the cases, it is necessary only to lift upwardly on the forward end of the key leg 50 and push rearwardly on the key. The shoulders 52 of the cams 51 will cause spreading of the abutment 46 and the walls 27 and 28 for removing the legs 48 from the recesses 43 of the locking members 42. Then by lifting the unlocked case so that the openings 41 are clear of the members 42 and then by pulling forwardly on the unlocked case to remove the tongues 39 from their engagement with the underside of the top wall 28, the case can be removed from the cabinet.

The thickness of the materials shown in the drawing, including the reenforcing ring 30, have been exaggerated for the purpose of clearly showing all of the elements of the invention, but it is apparent from the disclosure that when these materials are of proper thickness, I have provided an interlocking mechanism which requires only the minimum amount of space. Preferably the locking mechanism at the front end of the cases is interposed between the paths of the drawer gliders and therefore such mechanism does not obstruct or hinder the gliding move-

ment of the drawer. By using my improved interlock, the height of the gliders on the drawers may be very slight to cause the drawers to pass over the interlock.

While the form of embodiment of the present invention as herein disclosed constitutes a preferred form, it is to be understood that other forms might be adopted, all coming within the scope of the claims which follow.

I claim:

1. In combination, an element having an opening therethrough; a second element including a locking member having a part projecting through the opening in the first mentioned element and having an abutment spaced from and facing said first mentioned element; and a key for locking the member in the opening, said key including a leg extending between the abutment and the first mentioned element, said leg having a shoulder extending in the opening in the first mentioned element at an edge of said opening.

2. In combination, an element having an opening therethrough; a second element including a locking member having a part projecting through the opening in the first mentioned element and having an abutment spaced from and facing the first mentioned element; and a key for locking the member in the opening, said key including a leg extending between the abutment and the first mentioned element, said leg having a shoulder extending in the opening in the first mentioned element for abutting the first mentioned elements at an edge of said opening, the said shoulder forming a cam for moving the key in the direction of said abutment when the key is moved from the locking member.

3. In combination, an element having an opening therethrough; a second element including a locking member having a part projecting through the opening in the first mentioned element and having an opening in one end and having an abutment facing in the direction of said first mentioned element; and a locking key including a yoke, a leg extending from the yoke into the opening in the projecting part of the locking member, said leg having a shoulder extending in the opening in the first mentioned element for abutting the first mentioned element at an edge of said opening, and said key having a section extending from the yoke and alongside the projecting part of the locking member and engaging the first mentioned element.

4. In combination, an element having an opening therethrough; a second element including a locking member having a part projecting through the opening in the first mentioned element, said projecting part having an opening in one end and having an abutment facing in the direction of said first mentioned element and a shoulder on the wall opposite said opening; and a locking key including a yoke, a leg extending from the yoke into the opening in the projecting part of the locking member, said leg having a shoulder extending in the opening in the first mentioned element for abutting the first mentioned element at an edge of said opening, and said key having a section extending from the yoke and alongside the projecting part of the locking member, said section having a shoulder for abutting the first mentioned shoulder when the leg extends in the opening in the locking member, said section and leg being flexible and resilient with respect to one another so that the shoulder of the section can be

flexed over the locking member when the key is inserted or removed from the locking member.

5. In combination, an element having an opening therethrough one wall of the opening forming a shoulder; a second element including a locking member having a part projecting through the opening in the first element, said part having a shoulder facing in the same direction as the first mentioned shoulder, said locking member having an abutment spaced from and facing the first mentioned element; and a key for locking the member in the opening, said key including a leg extending between the abutment and the first mentioned element, said key having a shoulder facing the first mentioned shoulder when the leg is in the locking member and a section extending alongside the locking member, said section having a shoulder facing the second mentioned shoulder when the key is in locking position.

6. In combination, an element having an opening therethrough one wall of said opening forming a shoulder; a second element including a locking member having a part projecting through the opening in the first element, said projecting part having a shoulder facing in the same direction as the first mentioned shoulder, said locking member having an abutment spaced from and facing the first mentioned element; and a key for locking the member in the opening, said key including a leg extending between the abutment and the first mentioned element and a section adapted to extend alongside the locking member, said section being flexible and resilient with respect to the leg, said section having a shoulder adapted to be flexed over the locking member when the leg is inserted between the abutment and the first mentioned element, the last mentioned shoulder engaging the second mentioned shoulder when the key is in locking position, and means forming a second shoulder on the key, the last mentioned shoulder being adapted to engage the first mentioned shoulder, said shoulders coop-

erating for preventing accidental removal of the key from the locking member.

7. In combination, two generally flat elements arranged with outer surfaces in contact, one of said elements having an opening provided therein, an offset portion on the other element, said offset portion extending through the opening in the first element, and key means for preventing separation of said elements, said key means including a flat yoke with a plurality of legs extending therefrom in the same direction, the yoke and one leg engaging the inner surface of the first element on opposite sides of said opening, the other leg engaging the inner surface of said offset portion, the last mentioned leg having a shoulder facing toward said yoke and abutting the edge of the first element at said opening to prevent accidental withdrawal of said leg.

8. In combination, two generally flat elements arranged with surfaces in contact, one of said elements having an opening formed therein, an offset portion on the other element, said offset portion extending through the opening in said first element and engaging certain edges thereof, said offset portion having an abutment spaced from and facing said first element, said offset portion having an open side, and key means for securing said elements in position, said key means having a yoke portion with a tongue projecting into the open side of the offset portion of said second element, said tongue having a cam portion terminating in a shoulder, the combined thickness of said tongue and cam portion being greater than the relative distance between the first element and the abutment of said offset portion, said cam serving to flex adjacent portions of said elements during movement of said tongue into and out of said offset portion whereby said shoulder will engage an edge of said opening to prevent accidental withdrawal of said tongue.
